Primary Examiner — Robert M Spear*Assistant Examiner* — Marissa J Cash(74) *Attorney, Agent, or Firm* — Knobbe, Martens, Olson & Bear LLP(57) **CLAIM**

We claim the ornamental design for a vaping device, as shown and described.

DESCRIPTION

FIG. 1 is a perspective view of a front side of the vaping device;

FIG. 2 is a view of a left side of the vaping device;

FIG. 3 is a view of a right side of the vaping device;

FIG. 4 is a perspective view of a back side of the vaping device;

FIG. 5 is a top view of the vaping device;

FIG. 6 is a bottom view of the vaping device; and,

FIG. 7 is a front view of the vaping device.

The broken lines illustrate portions of the vaping device which form no part of the claimed design.

1 Claim, 3 Drawing Sheets# US D805,686 S
